UNITED STATES PATENT OFFICE.

JOSEPH L. EDLAND, OF BROOKLYN, ASSIGNOR OF ONE-HALF TO JOHN M. VAN ORDEN, OF NEW YORK, N. Y.

TYPE-WRITING MACHINE.

SPECIFICATION forming part of Letters Patent No. 489,072, dated January 3, 1893.

Application filed March 30, 1892. Serial No. 427,019. (No model.)

To all whom it may concern:

Be it known that I, JOSEPH L. EDLAND, of Brooklyn, Kings county, New York, have invented an Improved Type-Writing Machine, 5 of which the following is a specification.

This invention relates to a type writing machine of simple construction, which works rapidly and accurately and can be made at a reduced cost.

10 It consists in the various features of improvement more fully pointed out in the claims.

In the accompanying drawings: Figure 1 is a top view of the machine partly in section. 15 Fig. 2 a longitudinal section on line z, z , Fig. 1, with the type wheel omitted. Fig. 3 a cross section on line y, y , Fig. 1 and Fig. 4 a longitudinal section on line z, z , Fig. 2.

The letter a , represents the bed plate of the 20 machine provided with a pair of rails a' , for guiding the carriage a^2 . In the uprights of this carriage is hung a rubber roller a^3 , which constitutes the feed roller and upon which the paper is held by the fingered guard e . 25 The paper is fed by revolving the roller a^3 , by means of a button a^4 , from the front toward the rear, as will be readily understood.

To feed the carriage a^2 , from right to left, after the formation of each letter the carriage 30 is provided with a rack a^5 , engaged by a pawl which in turn is operated by the printing lever in manner hereinafter described.

In front of the carriage a^2 , there is pivoted to the bed plate a , by pin b' , a lever b , normally held down by a spring c (Fig. 4). The lever b , is provided with a hub b^2 , to which there is attached by a screw b^3 , or otherwise an upwardly projecting post b^4 . This post is provided with a gear wheel b^5 , keyed thereto, 40 while above the gear wheel the annular type wheel d , is mounted upon the shaft, so as to revolve therewith. The type wheel d , is provided with three more or less sets of type, numerals, &c. of which each set is arranged in one horizontal row d', d^2, d^3 . The forward free end of the lever b , is engaged by the rear end of the printing lever f , which passes beneath lever b , (Fig. 3). The lever f , is in turn pivoted at g' , to an arm g , provided with a 45 toothed segment g^2 , that engages the gear wheel b^5 . The toothed segment turns on a

55 pivot g^3 , that passes through a fixed bracket g^4 , projecting upwardly from bed plate a . The front of the bed plate a , is provided with a corrugated flange h , and in rear thereof with the letters of the alphabet and with the numerals, signs, &c. to be printed.

The operation of the machine as thus far described will be readily understood. The printing lever is first revolved so as to engage the notched flange h , above the letter to be reproduced. This will by segment g^2 , and gear wheel b^5 , revolve the type wheel d , so as to bring the corresponding letter or sign opposite the roller a^3 . By next depressing the 60 printing lever, the lever b , and the post b^4 , will be tilted backward and against the roller a^3 , so that the letter previously brought into alignment therewith will be printed upon the paper carried by the roller. Upon the release 70 of the printing lever, the spring c , will return the parts to their normal position. To prevent any of the adjoining parts of the type wheel from reaching the paper, a perforated guard h' , is arranged between roller and type 75 wheel. The feeding of the carriage a^2 , is effected by a pawl i , engaging the rack a^5 . The pawl i , is provided with a bent arm i^2 , pivoted at i^3 , and projecting beneath lever b . A spring 80 i^3 , secured to the bent arm and which is weaker than the spring c , has a tendency to draw the pawl to the right. It will be seen that after a letter has been printed, and the printing lever is released, the lever b , in swinging down with its front free end will bear upon 85 the arm i^2 , of pawl i , and thus cause the pawl to vibrate to the left and to push the rack a^5 , and carriage a^2 , in the same direction for the distance of one tooth. Upon the next depression of the printing lever and the consequent 90 raising of the lever b , off the arm i^2 , the spring i^3 , will draw the pawl i , to the right and into engagement with the next tooth of the rack a^5 , ready for the next operation. Thus the proper feed from right to left is accomplished. 95

In order to sound the alarm at the end of each line, a bell crank lever j , pivoted to bed plate a , is oscillated by the right hand upright of carriage a^2 , when the latter arrives at its extreme left hand position. The bell 100 crank lever j , is by spring j' connected to the bent pivoted hammer j^2 , striking the bell j^3 .

It will be seen that in order to bring either of the lower horizontal rows d^2, d' , opposite to the perforation in plate h , the type wheel d , must be raised more or less upon its post b^4 .

5 To this effect, the lower edge of the type wheel is engaged by a fork k , moving vertically in a fixed way k' . The fork k , may be raised by two more or less levers k^2, k^3 , one lever for each horizontal row of the type wheel in excess of the uppermost row. The levers k^2, k^3 , are pivoted to suitable projections on the bed plate a , and tilt to different degrees. When one of the levers is depressed at its free end, the type wheel will be correspondingly raised 10 upon its post b^4 , and thus the horizontal row d^2, d' , desired, will be in position for printing. As long as this row is used, the lever k^2 , or k^3 , should be held down by the hand or otherwise. The type is inked in the ordinary or 15 in any desirable manner, preferably by applying an inking pad h^2 , to face of plate h' .

What I claim is:

1. A type writer comprising a tilting post, a type wheel and gear wheel mounted there-

on, a printing lever adapted to tilt the post, 25 a fixed bracket, and a toothed segment engaging the gear wheel and pivotally connected to the printing lever and to the fixed bracket, substantially as specified.

2. A type writer comprising a tilting post, 30 a vertically adjustable type wheel mounted thereon, hand levers k^2, k^3 , for raising the type wheel, a lever b , and printing lever f , for tilting the post and a gear wheel b^5 , and toothed segment g^2 , for revolving the post, 35 substantially as specified.

3. A type writer comprising a feed carriage a^2 , having rack a^5 , a spring pawl i , engaging the same and having bent arm i^2 , a lever b , engaging the bent arm, a post mounted upon 40 the lever and carrying the type wheel, a printing lever and toothed segment for tilting and revolving the post and a spring c , bearing upon lever b , substantially as specified.
